P. B. JOHNSON.
THERMOSTAT.
ORIGINAL FILED OCT. 26, 1920.

Fig. 2.

Inventor
Peter B. Johnson
Attorney
Frank Warren

UNITED STATES PATENT OFFICE.

PETER B. JOHNSON, OF SEATTLE, WASHINGTON.

THERMOSTAT.

Application filed October 26, 1920, Serial No. 419,694. Renewed March 16, 1922. Serial No. 544,369.

To all whom it may concern:

Be it known that I, PETER B. JOHNSON, a citizen of the United States, residing at Seattle, in the county of King and State 5 of Washington, have invented a certain new and useful Improvement in Thermostats, of which the following is a specification.

My invention relates to improvements in thermostats and is an improvement upon the 10 thermostat shown in my co-pending application for United States Patent, Serial No. 388,661, filed June 12, 1920, and the object of my invention is to provide a thermostat for an oil burner wherein a valve interposed 15 between the source of fluid fuel and the said burner is automatically closed by thermodynamic action upon cooling, thereby eliminating any possibility of explosion or fire.

Another object is to provide a thermostat 20 which will functionally retain a valve in a fixed position relative to the constant amount of heat, thereby insuring a steady supply of fluid fuel.

A further object is to provide a thermostat 25 embodying simplicity, durability and economy in construction, that may be readily applied to oil burners, that is positive and efficient in operation and that will not readily get out of order.

With the above and other objects in view 30 which will appear as the description proceeds the invention consists of the novel construction, arrangement and combination of parts hereinafter described and claimed.

I accomplish these objects by devices illustrated in the accompanying drawings, where- 35 in—

Figure 1 is a view in perspective of a thermostat embodying the features of my in- 40 vention; and

Fig. 2 is a view in side elevation of same attached to an oil burner.

Referring to the drawings, throughout 45 which like reference numerals designate like parts, the numeral 10 designates a thermostatic bar having an aperture 11 in one end the opposite end thereof being slightly enlarged as at 12.

Downwardly projecting standards 13 and 50 14 are rigidly secured to the enlarged portion 12 and a downwardly depending arm 15 is pivotally secured thereto as at 16.

A valve 17 is fixedly secured to the lower end of the standard 13 and is provided with

a tubular shank 18 adapted to be connected 55 with an inlet supply pipe, not shown.

The valve 17 is adapted to be opened and closed by a valve stem 19 having a lever arm 20 mounted thereon and adjustably secured thereto by a set screw 21. The outer 60 end of the valve stem 19 is pivotally mounted in the lower end portion of the standard 14, as at 22.

The upper end portion of the lever arm 20 has a slot 23 formed therein and is pro- 65 vided with a cross pin 24 over which the bifurcated end 25 of the arm 15 is arranged to fit. A reduced pipe 26 is arranged to communicate with the valve 17 and has an enlarged coupling member 27 provided on 70 its opposite end. A hole 28 is provided in the arm 15.

In Fig. 2 of the drawings, I have shown my thermostat applied to one form of an oil burner 29 wherein the aperture 11 pro- 75 vided in the thermostat bar 10 is fitted over the upper reduced portion of an end plate 30 and is thereby held against thrust move- ment.

The enlarged portion 12 of said bar 10 80 is slidably mounted in a slot provided in the upper portion of an end plate 31 and the arm 15 is fulcrumed to a bracket 32 fixedly secured to said end plate by a pivot pin 33 which is passed through the hole 28. 85

The coupling 27 is connectively secured to the burner coil 34 functionally mounted in the burner 29 and having an outlet or burner end 35.

Referring to Fig. 2 of the drawings it 90 will be obvious that when initial heat is created by lighting the priming fluid fuel the thermostat bar 10 will become heated and will expand. As the bar 10 is secured against longitudinal movement at the point 95 11, it will expand lengthwise from this point and the enlarged portion 12 will slidably move to the left as said bar becomes elongated.

The arm 15 being pivotally connected 100 with the bar 10 as at 16, and fulcrumed to the burner 29 as at 33 will be actuated to the position shown in Fig. 2 and the lower end of same will carry the upper end of the lever arm 20 therewith thus opening the 105 valve 17. The standards 13 and 14 being rigidly secured to the bar 10 will move in unison therewith and it will be obvious that

2
the counter movement thereof will assist the functional operation of the valve 17.

Liquid fuel now being free to enter the burner through the opened valve 17 will be-
5 come gasified within the burner coil 34 and may be ignited at the burner outlet 35. A constant radiation of heat will be diffused through the burner and the bar 10 will thereby assume a constant length holding
10 the valve 17 open at a fixed point and thus permitting a steady supply of fuel to enter the burner.

If at any time the burner should accidentally or otherwise become extinguished when
15 unattended it will be obvious that the cooling and contraction of the bar 10 will automatically close the valve 17 thereby eliminating the danger of flooding the burner with fuel and the consequent possibility of
20 explosion and fire. It will be apparent that the valve 17 may be set to any angular position by means of the screw 21.

From the foregoing description taken in connection with the accompanying drawings
25 the advantages of the construction and the method of operation of thermostat will be readily apparent to those skilled in the art to which the invention relates, but, while I have described the principle of the operation
30 of the invention together with the device which I now consider to be the best embodiment thereof, I desire to have it understood that the thermostat shown is

merely illustrative and that such changes may be made as are within the scope of the 35 following claim.

What I claim is:

A thermostat comprising a thermostatic bar having means disposed at one end thereof for rigidly securing same to a heat generating device, the other end of said bar being free to elongate or contract relative to said heat generating device, said bar being composed of material adapted to be functionally elongated by heating and contracted by cooling, downwardly projecting standards rigidly secured to the free end of said thermostatic bar, a valve adapted to control the supply of the fluid fuel for a heat generating device fixedly secured to the 50 lower end of one of said standards, a stem on said valve having one end pivotally mounted in the other of said standards, a lever arm adjustably secured to said stem, an arm pivotally secured to said thermostatic bar and adapted to be fulcrumed to a heat generating device, and said arm being pivotally connected to said lever arm and adapted to open and close said valve by expansion and contraction of said thermostatic 60 bar.

In witness whereof I hereunto subscribe my name this 19th day of October A. D. 1920.

PETER B. JOHNSON.
